UNITED STATES PATENT OFFICE.

EMILE G. PERROT, OF PHILADELPHIA, PENNSYLVANIA.

BUILDING.

1,342,062.

Specification of Letters Patent.

Patented June 1, 1920.

Application filed February 18, 1918. Serial No. 217,787.

To all whom it may concern:

Be it known that I, EMILE G. PERROT, citizen of the United States, and resident of Philadelphia, county of Philadelphia, and 5 State of Pennsylvania, have invented an Improvement in Buildings, of which the following is a specification.

My invention has for its main object the construction of buildings, comprising 10 wooden framing and concrete or equivalent outer walls, which will combine strength, dryness, fireproof qualities and economy in cost of construction.

More specifically my object is to provide a 15 construction of building which permits the skeleton or balloon framework under roof to be first erected, including the floor joists and roofing timbers, and thereafter to be coated with an outer covering of concrete or equivalent material and an inner wall covering of lath and plaster, the skeleton frame work providing within itself the essentials of forms for molding the studs or posts and plates of concrete or equivalent material, 20 preferably reinforced, and in which the molded studs or posts are integral with the outer wall covering of concrete or its equivalent and the plates integrally connecting with the studs or posts.

Another object of my invention is to dispense with or avoid the necessity of using removable temporary forms with which to mold or shape the concrete employed in the walls, the studs or posts and plates thereof; 35 and in lieu therefor, employ the wooden studing, not only for receiving and holding the paper or equivalent backing and expanded or open metal work as a support on the outside for the concrete outer wall and also as 40 the equivalent of furring to support the lath and plaster of the inner walls, but also by properly spacing said studs and the providing of ledger boards (so called), to cause them to provide vertical channels of proper

45 width, unsealed at the outside, to be filled with concrete (preferably reinforced) and formed integral with the outer wall covering of concrete and also to provide horizontal channels to receive concrete (preferably reinforced) forming the sills or stringers which are preferably integral with the outer walls and also at intervals along their length with the concrete studs.

My object is further, in a building structure of the character above designated, to 55 provide the skeleton framework with hori-

zontal ledger-boards with bottoms attached, said ledger-boards resting upon the wooden studs of the lower floor and supporting the floor joists of the second floor and which, 60 aside from acting as a means of tying the studs and joists together, further act as a mold for receiving the concrete (preferably reinforced) which constitutes concrete plates integral with the vertical concrete studs and 65 extending more or less around the building to tie or bind it together and to reinforce and strengthen the outer walls in a horizontal direction, just as the concrete studs reinforce it in a vertical direction. 70

My object is further to construct a house having reinforced concrete walls of low first cost and at the same time have it possess the fire-resisting qualities inherent in the conventional house built of brick; and further, 75 to provide a reinforced concrete walled house having a skeleton frame, first employed as a form to shape the house and later as furring for the lath and plaster or party walls of concrete, whereby a dry house may be in- 80 sured.

My invention also consists of improvements hereinafter described whereby the above objects and results are attained, said improvements comprising certain organization and combination of parts which are 85 fully described hereinafter and more particularly defined in the claims.

For the purpose of illustrating my invention, I have shown in the accompanying 90 drawings the embodiment thereof which is at present preferred by me, since the same is in form to give satisfactory and reliable results, but it is to be understood that the several instrumentalities of which my invention 95 consists, can be variously arranged and organized and that my invention is not limited to the precise arrangement and organization of the instrumentalities herein shown and described. 100

Referring to the drawings: Figure 1 is a perspective view, partly in section and partly broken away to show my improved construction of building; Fig. 2 is a sectional-plan view of a portion of my improved building; Fig. 3 is a vertical section taken on line 3—3 of Fig. 1; Fig. 4 is a horizontal sectional view on line y—y of Fig. 5 showing the preferred construction of party wall; Fig. 5 is a vertical section 105 through the party wall at the level of the second floor; and Fig. 6 is a vertical section

through a side wall of the full height of a house and embodying my invention.

2 is the concrete foundation and of any suitable construction; and 6^a are the lower floor joists and rest upon the foundation 2. The wooden studs 3 and part of studs 3^a are set up on floor joists 6^a and the rest upon foundation 2, and assuming that the building is to be of a two-story design, then the 10 upper ends of these studs are connected together in spaced relation by the vertical ledger-boards 5 provided with the bottoms 4, which are firmly nailed to the tops of the studs. The studs 3^a are arranged in pairs 15 and closer together than the studs 3 in their relation to each other or to the said studs 3^a (Fig. 2). The narrow space between the pairs of studs 3^a is subsequently filled with reinforced concrete 18 as shown and more 20 fully described hereinafter. At the corners of the building these studs 3 are set at right angles to provide a vertical corner pocket or recess which is filled with concrete 18^a (Fig. 2). In this manner the studs are employed not only as studding in erecting the 25 skeleton or balloon framing, but also as means to shape or mold the vertical ribs or studs of concrete and subsequently act as furring timbers for the walls.

30 The second floor joists 6 rest upon the ledger boards 5 with their ends projecting to a plane flush with the outer surfaces of the studs 3, 3^a. Nailed upon these joists 6 are the wooden strips or plates 7; and resting upon these plates and preferably in alinement with the joists 6 are the second story studs 8 and 8^a which are spaced apart to correspond to the spacing of the lower or first story studs 3, 3^a. The studs 8^a are arranged in pairs immediately over the studs 3^a and provide a narrow vertical channel which is subsequently filled with reinforced concrete 18 as a continuation of that formed between the studs 3^a and above referred to, 40 (Fig. 1). The studs 8^a of each pair are closer together than the adjacent floor joists 6 and consequently one of these studs 8^a of each pair is continued down and rests upon the ledger-board 5, as shown in Fig. 1. 45 This same arrangement would also preferably be followed at the level of the first floor joists 6^a, but I do not restrict myself in such details.

The tops of the studs 8 and 8^a are secured 55 to a ledger-board 10 having the bottom 9 which is nailed or otherwise secured to the studs. The roof joists rest in notched portions of the ledger-board 10 and support the roofing 11 of any suitable character. It will 60 be noted in Fig. 6, that the horizontal spaces between the board 9 and the roof 11 and backed by the ledger-board 10, is filled with reinforced concrete 21 and thereby provides a horizontal concrete stringer or sill 65 around the top of the wall to receive the

weight of the roof and also to tie the structure horizontally.

The space formed by the ledger-board 5 and its bottom at the level of the second floor joists, is filled with reinforced concrete 18 70 and acts as a concrete sill for the floor joists and also to tie the structure horizontally while strengthening the outer wall 17.

Having erected the skeleton or balloon framing of the building and also having 75 temporarily or permanently closed the inner sides of the vertical channels formed by the studs 3^a and 8^a (which may be done by heavy building paper strips or by the lath and plaster 19), heavy building paper 12 is nailed to the outside of the studs and bottoms 4 and 9 of the ledger boards, but does not extend over the spaces between the pairs of studs 3^a 80 and 8^a nor over the spaces to be filled with concrete to form the stringers or sills 15 and 21, as will be clearly understood by reference to the drawings. Over this heavy building paper and over the spaces not covered by the paper is stretched the expanded metal work 90 or meshed wire layer 13, the same being nailed in place at 14, upon the joists and bottom boards 4 and 9 of the ledger-boards, thereby forming a metal mesh opening into the vertical spaces between the pairs of studs 95 3^a and 8^a and also into the horizontal spaces formed by the ledger-boards, but closed at all other portions (except at the corners of the building) by the paper backing 12. At the corners of the building the meshed metal 100 13 from the two right angle walls meets to form an inclosed vertical channel to be subsequently filled with concrete at 18^a, Fig. 2. The bottoms 4 for the ledger boards, while preferably of wood, may be made of any 105 suitable material as will hold the concrete in position while setting.

When the studs are thus sheathed on the outside with the building paper and expanded metal or meshed wire, the concrete is applied, preferably by a "gun", or by hand if desired. It is best that the channels to be filled with concrete shall be reinforced with steel rods 16, said rods wired in position in the usual manner and to the outer 110 meshed metal 13; there being one or more of such rods to each of the concrete studs 18 and 18^a and horizontal sills 15 and 21, as preferred.

The concrete is then applied by the use 120 of a "cement gun" and where the building paper is back of the metal mesh 13 the cement does not pass into the spaces 20 between the studs, but builds around the metal mesh 13 and outward for the desired thickness, say one and one-half to two inches; and at the same time, the concrete is projected through the metal mesh and into the spaces between the pairs of studs 3^a and 8^a 125 to form the vertical concrete studs 18 ex- 130

tending from the foundation to the roof, also into the spaces between the studs 3 at the corners of the building to form corner concrete studs or posts 18^a extending from 5 the foundation to the roof, and also into the horizontal spaces formed by the ledger-boards at the level of the second floor joists and at the roof to form the horizontal concrete sills or plates 15 and 21 respectively. 10 In this manner, the concrete walls 17 are reinforced by the expanded metal or mesh 13 and are strengthened by the reinforced concrete studs 18 and 18^a and the reinforced horizontal sills or stringers 15 and 21, all 15 held together as an integral reinforced structure.

Concrete when applied with a "gun" is 33 per cent. denser than ordinarily poured concrete and about twice as strong and hence 20 preferable, not only because with a given quantity of material a stronger structure is secured, but also because, for a structure of the same strength less material is required and hence economy is available. But while 25 I prefer the cement to be applied with a "gun," this is not always available and therefore my invention is not so restricted and the cement may be applied with a trowel and the sills and studs poured, or 30 otherwise, as found most convenient or desirable under the conditions prevailing.

In my foregoing description, I have described the construction in regard to the outer walls of the building and this has 35 been more particularly in considering the building as a single house; but in cases where these houses are put up in rows, it then becomes necessary to provide a suitable party wall which shall have fire-proof qualities, and this would not be satisfactorily 40 attained if the lathing and ordinary plaster were used, as indicated at 19. I therefore prefer, where party walls are to be employed, to construct them in the manner indicated 45 in Figs. 4 and 5. In these figures, it will be observed that the general construction is similar to that employed for the outside walls of the building, but with the addition of substituting for the lath and plaster, a 50 duplicate concrete wall of building paper, expanded metal and concrete. These party walls will therefore have two concrete walls 17^a connected at intervals by the concrete studs 18^a which may be metal reinforced at 55 16. The wooden studs 3 and 3^a are employed as in the outer walls and provide the hollow spaces 20 and at the same time act as furring for supporting the paper 12 and the expanded metal 13 in position. In the case 60 of the concrete sills or stringers 15^a these would be united to one of the walls 17^a and to the vertical concrete studs 18^a and through them integrally connected with the other wall 17^a which would correspond to the lath 65 and plaster of the outer wall. The floor

joists 6 passing from each of the buildings are lapped and each rests upon the ledger-board 5 and upon the concrete sills 15^a when completed, (Fig. 5).

I have described my improved building as 70 of a two-story character, but it will be understood the same general plan of procedure and construction may be employed where there is only one story to the building or where there are more than two stories, 75 as may be required or desirable. It will also be understood that whether the joists 6 for the upper stories are employed or not, the feature of the concrete sills or stringers 15 may, if desired be employed at intervals 80 between the foundation and roof.

The construction of houses in the manner herein described has particular utility in cases where it is necessary to quickly erect buildings of more or less fire-proof character and from material which is easily available. 85

The main studs, ledger-boards and plates, which act as a furring in the finished building, are erected in such manner as to not 90 only support the floor joists and rafters, but also act as forms in conjunction with the expanded or meshed metal for the cementitious envelop which is to be applied, the application thereof being after the entire 95 skeleton or balloon frame of the building has been erected. It will be seen, therefore, that the skeleton frame may constitute part of the furring in a finished building as well as provide forms which remain within and 100 as a part of said finished structure for properly shaping and strengthening the studs, plates and outer wall of cementitious material and to insure the desired pre-determined configuration to be given to the building. 105

I have described my improvements more particularly for cheap and rapid erection and with the elimination of necessity for skilled labor, but I do not confine myself to the details: for example, while a concrete 110 mixture applied with a "gun" is most preferable, facilities for such application are not always available and hence the cementitious material may be placed in position by hand, poured or otherwise applied, as found desirable or necessary; the cementitious material may be cement having a body of sand or it may be concrete or any tenacious material of mortar characteristics and I include these when I refer to concrete, cement or 115 cementitious material; also, while the relatively impervious sheathing of building paper back of the meshed metal may be desirable, nevertheless, it may be dispensed with if preferred, as the cementitious wall 120 covering may be back plastered on the inside of the meshed metal before the inner wall or covering is applied; while lath and plaster give a fine finish for the interior, it is manifest that other wall coverings or 125 130

sheathings may be employed instead, where cheapness is necessary; while the skeleton frame is, in cheaply constructed buildings, formed of wood, I do not confine myself to the use of wood, as any substitute therefor in whole or in part may be employed as building practice may dictate; and finally, when I use the term "ledger-board," I do not restrict myself to a structure formed of wood, but use it in the generic sense as defining a structure for temporary support of floor joists or rafters, irrespective of its detail structure.

It will now be apparent that I have devised a novel and useful construction which embodies the features of advantage enumerated as desirable, and while I have in the present instance shown and described the preferred embodiment thereof which has been found in practice to give satisfactory and reliable results, it is to be understood that I do not restrict myself to the details, as the same are susceptible of modification in various particulars without departing from the spirit or scope of the invention.

Having now described my invention, what I claim as new and desire to secure by Letters Patent, is:—

1. In a building of combined cementitious material and frame, the combination of a self supporting skeleton frame including vertical studs of wood arranged relatively close together in pairs and the studs at the corner of the building arranged at right angles to each other and with their inner portions relatively closer than their outer portions, meshed metal extending over the outside of the frame of the building and across the spaces between the studs, and cementitious material applied to and supported by the meshed metal to form a continuous outer wall and also extending through the meshed metal into the spaces formed between the closely arranged studs of the pairs both in the sides and at the corner, whereby vertical studs of cementitious material integral with the outer cementitious walls are provided, the wooden studs first constituting a part of the self supporting and permanent skeleton framing and then providing a permanent framing within the wall structure of the building suitable for furring and also acting as the molds when forming the studs of cementitious material.

2. In a building of combined cementitious material and frame, the combination of a self supporting skeleton frame including vertical studs of wood arranged relatively close together in pairs and the studs at the corner of the building arranged at right angles to each other and with their inner portions relatively closer than their outer portions, meshed metal extending over the outside of the frame of the building and across

the spaces between the studs, a wall covering secured upon the inner edges of the studs and closing the spaces between them on the inside of the building, and cementitious material applied to and supported by the meshed metal to form a continuous outer wall and also extending through the meshed metal into the spaces formed between the closely arranged studs of the pairs both in the sides and at the corner, whereby vertical studs of cementitious material integral with the outer cementitious walls are provided, and extending inward to the inner wall covering, the wooden studs first constituting a part of the self supporting and permanent skeleton framing and then providing a permanent framing within the wall structure of the building suitable for furring and also acting as the molds when forming the studs of cementitious material.

3. In a building studs of wood spaced apart with a portion of said studs arranged in pairs nearer together than general spacing of the studs, combined with a retaining covering stretched over the outer sides of the studs except at the spaces between the closely arranged studs of the pairs, a meshed metal covering secured in place upon the studs and over the retaining covering and also extending across the spaces between the closely arranged studs, and cementitious material extending through and supported by the meshed metal covering and backed by the retaining covering said material also extending through the meshed metal covering and filling the vertical spaces between the respective closely arranged studs of the pairs, whereby the outer wall of the building is reinforced by the meshed metal and is provided with integrally connected upright studs of cementitious material, the said wooden studs forming a portion of the initial framing of the building and also constituting furring thereof and permanently retained mold forms for the studs of cementitious material.

4. A building, comprising a permanent self-supporting skeleton frame extending from foundation to roof and covered on the outside with a wall of cementitious material reinforced by meshed metal secured to the outside of the skeleton frame and having integral vertical studs and horizontal sills of cementitious material on its inner side, the said skeleton frame adapted to support the roof and including vertical wooden studs arranged closely together in pairs to provide fixed vertical mold forms and also including horizontal mold forms, for shaping the said vertical studs and horizontal sills of cementitious material.

5. In a combined frame and cement building, a skeleton frame including closely arranged studs in pairs, floor joists and a ledger-board upon which the joists rest, said

- ledger-board having a suitable bottom to support cementitious material, meshed metal covering the outside of the framing and extending across the space between the closely arranged studs of the pairs and also in front of the ledger-board, and cementitious material extending entirely over the meshed metal and through it, and also filling the vertical spaces between the closely arranged studs of the pairs to form vertical studs of cementitious material continuous above and below the joists and also filling the space formed by the ledger-board and bottom to provide a sill of cementitious material, said studs and sill integrally connecting and also integral with the outer wall of cementitious covering material through the meshed metal.
6. In a combined frame and cement building, a skeleton frame including closely arranged studs in pairs, floor joists and a ledger-board upon which the joists rest, said ledger-board having a suitable bottom to support cementitious material, a relatively impervious covering fastened to the outside of the studs but leaving the spaces between the closely arranged studs of the pairs and in alignment with the ledger-board unobstructed, meshed metal covering the outside of the framing and the impervious covering and extending across the space between the closely arranged studs of the pairs and in front of the ledger-board, and cementitious material extending entirely over the meshed metal and through it, to the impervious covering and also filling the vertical spaces between the closely arranged studs of the pairs to form vertical studs of cementitious material continuous above and below the joists and also filling the space formed by the ledger-board and bottom to provide a sill of cementitious material said studs and sill integrally connecting and also integral with the outer wall of cementitious covering material through the meshed metal, and an inner lining supported by the inner edges of the studs and by the ledger-board, the said studs forming both the furring for the inner lining, a permanent part of the skeleton framing, and also a permanent mold for the studs of cementitious material and similarly the ledger-board constituting a part of the skeleton framing, a portion of the furring and permanent mold for the sill of cementitious material.
7. In a building structure the combination of a skeleton frame including studs, floor joists, and ledger-board structure adjacent to and supporting the second-floor joists and also arranged at the upper ends of the studs, said ledger board structures each provided with a suitable horizontal bottom for supporting cementitious material, a portion of the studs being arranged relatively far apart and a portion arranged in pairs relatively close together, a relatively close covering fastened upon the outer edges of the studs and terminating adjacent to the ledger-board structures and leaving the outer side of the spaces between the closely arranged studs of the pairs and the outer sides of the ledger-board structures exposed, meshed metal arranged entirely over the outside of the studs, ends of the floor joists and ledger-board structures, and hardened cementitious compound forming an outer wall over the meshed metal and up to the relatively close covering and also filling the vertical spaces between the closely arranged studs of the pairs to form vertical continuous studs of cementitious material of approximately the entire height of the building and said cementitious material also filling the spaces formed by the ledger-board and bottom structures to provide horizontal sills or stringers of cementitious material, said studs and sills of cementitious material integral with each other and with the outside wall, studs of the skeleton frame and the ledger-board structures constituting a permanent part of the frame structure and also acting as permanently retained mold forms for the cementitious material.
8. A structure for buildings consisting of a permanent self-supporting skeleton frame comprising studs part of which are arranged closely together in pairs, joists, and ledger-boards and extending from foundation to roof, combined with an outer covering of cementitious material supported by the studs, and vertical studs and horizontal sills or stringers also formed of cementitious material and connected with each other and the sills integral with the outer cementitious covering, said cementitious studs and sills being reinforced with metal and permanently combined with and in contact with the closely arranged pairs of studs and ledger-boards of the skeleton frame.
9. A building formed of a permanently combined self-supporting skeleton frame extending from the foundation to the roof, and integrally united vertical studs and walls of cementitious material, characterized by the framing being so constructed as to provide permanent self-supporting vertical studs forming a part of the skeleton frame and sustaining an outer wall of reinforced cementitious material, said studs being in part arranged closely together in pairs to constitute permanent inner molds for shaping and bounding the vertical studs of cementitious material.
- In testimony of which invention, I hereunto set my hand.
